UNITED STATES PATENT OFFICE.

JOHN V. HORR, OF CLEVELAND, OHIO, ASSIGNOR TO THE INTERNATIONAL SIGN COMPANY, OF CLEVELAND, OHIO, A CORPORATION OF OHIO.

DISPENSING-CARTON.

1,367,048.

Specification of Letters Patent. Patented Feb. 1, 1921.

Application filed March 9, 1917. Serial No. 153,686.

To all whom it may concern:

Be it known that I, JOHN V. HORR, a citizen of the United States, residing at Cleveland, in the county of Cuyahoga and State 5 of Ohio, have invented a certain new and useful Improvement in Dispensing-Cartons, of which the following is a full, clear, and exact description.

This invention relates to a carton which 10 serves not only the purpose of a receptacle in which articles may be packed and stored, but also is provided with certain features which enable it to be used as a dispensing carton, from which the goods may be dispensed 15 and removed as sales are made.

The object of the invention is to provide a carton which has certain features particularly adapting it for this use. Generally speaking, the invention may be said to comprise 20 the elements and combinations thereof set forth in the accompanying claims.

Reference should be had to the accompanying drawings forming a part of this specification, in which Figure 1 is a perspective 25 view showing a dispensing carton in one position in which it may be used; Fig. 2 is a perspective view showing a dispensing carton in another position in which it may be used; Fig. 3 is a side elevation of the carton shown in Fig. 1, and Fig. 4 is a rear elevation of the carton shown in Fig. 1. Fig. 5 is a plan view of a blank from which such a carton as shown in Fig. 1 may be formed; Fig. 6 is a top view of a blank for forming 30 a carton such as shown in Fig. 2.

Referring to Fig. 1, the body of the carton may be indicated generally at 1. This body is provided with a top face 2, forming a part of which is a collapsible cover, such as indicated at 3. This cover is cut from the portion forming the top surface or face of the carton, and is folded adjacent the middle portion, and is provided with slots which engage with corner pieces such as indicated 40 at 4, these corner pieces serving to hold the cover in substantially vertical position. The cover may carry advertising matter descriptive of the goods which are contained within the carton. The removal of the cover and the positioning of the cover as shown in Fig. 1 exposes the articles within the carton.

Extending from the body of the carton there are two easel members one of which is shown at 5 in Fig. 1, there being a corresponding easel member secured to the oppo-

site portion of the carton. These easel members are provided with two sides indicated at 6 and 7, which sides extend at an angle with respect to each other. The easel members 5 are held in proper position so as not to spread by a retaining member, which does not appear in Figs. 1 and 2, but which will be later explained, which retaining member is provided with projections such as indicated at 8 that extend through suitable slots 65 formed in the easel members.

The easel members support the body of the carton in such position as to permit an easy display and observation of the articles within the carton, and the gentle incline given to the body may be sufficient to cause the articles within the body as they are removed by sale to descend toward the lower part of the carton, so as to be easy of access to a purchaser.

The form of carton shown in Fig. 2 so far as the general features of supporting the body is concerned, are in all substantial particulars the same as that shown in Fig. 1, except that the carton instead of being supported or resting upon the edge 6 of the easel members 5, is supported upon and rests upon the edges 7 of the easel members 5. This then supports the body portion in a more upright position, which may be more desirable in connection with the dispensing of articles which may be contained therein.

Because the carton when supported in the position shown in Fig. 2 is in a more nearly vertical position, it becomes desirable to provide some means for preventing the articles contained within the carton from any danger of falling out. This feature is taken care of by the provision of strips 9 which extend sufficiently far from the edges of the carton to overhang the ends of articles which may be contained within the carton, and so prevent their falling out of the carton. Furthermore, these portions 9 in connection with the sides and bottom of the carton form guides which suitably guide the articles within the carton, and they may descend in the carton when these articles are removed at the lower part of the carton, and it will be observed that provision for the removal of these articles is made at the lower part of the carton by providing an opening 10.

Fig. 5 shows a blank from which the carton shown in Fig. 1 may be formed. The blank is cut from a single sheet of material 110

from which the carton is to be formed; the blank provides a face portion 12, primary side members 13, secondary side members 14, a back 15, a retaining member 16, and supporting members 5 and the foldable cover 3.

Of course there are corner folds which are provided on the blank, but these being merely incident, no particular description need be given of them. The blank is folded 10 upon the line shown to be dotted in the figure. As before explained the retaining members 16 when the blank is properly folded are in such position that the extensions 8 thereof will extend through the slots 15 5^a formed in the supporting members 5. Thus the supporting members 5 are rigidly secured to the body of the carton.

The cover is formed by cutting all around the edges shown in full lines, and creasing 20 the material at the points indicated at 3^a and 3^b. This permits the cover 3 to fold along the line 3^a and along the lines 3^b. The cover at the lower end is provided with cut portions 3^c through which cut portions the extensions 2 pass when the cover is in its folded position.

The blank shown in Fig. 6 is in all particulars the same as the blank shown in Fig. 5, with the exception that that portion of 30 the blank which is to form the top of the carton is provided with a cut out portion indicated at 16, which cut out portion is enlarged transversely with respect to the opening 16, as indicated at 17. The opening 35 16 in the top portion is such as to provide the extensions 9 which retain the articles within the carton and guide them as they descend toward the opening 17 from which opening articles may be removed as they are sold.

40 It will be seen from the foregoing description that the body of the carton may be supported in either of two positions, and that the easel supporting members 5 are so fashioned as to permit the body of the carton to be thus supported, the difference between the two forms of the carton herein indicated are merely differences in the manner of forming the top face of the carton.

Having described my invention, I claim:—

50 1. A dispensing carton comprising a body portion adapted to contain articles to be dispensed, easel supporting members for the said body portion and attached to the body portion, retaining means hinged upon the body portion engaging the easel supporting members at portions thereof which are remote from the box thereby joining the easel members to each other.

60 2. A dispensing carton comprising a body portion adapted to contain articles to be dispensed, easel supporting members for said body portion and attached to the body portion, a retaining member carried by the body portion and adapted to extend between the easel supporting members, coöoperating

means upon the retaining member and the easel supporting members at portions of said easel supporting members remote from the body portion thereby forming a rigid connection.

70 3. A dispensing carton comprising a body portion adapted to contain articles to be dispensed, easel supporting members for the body portion and attached to the body portion, said members being provided with 75 edges which extend at an angle with respect to each other whereby the body may be supported in different positions upon the edges of the supporting members and means hingedly connected to the body portion adjacent one end thereof, and extending between the easel members, the said means and the easel members having coöperating portions whereby they may be secured to each other and rigidly held in position.

80 4. A dispensing carton comprising a body portion having a front face which has open portions to display the articles within the carton and from which the articles may be removed, supporting members secured to the 85 carton body portion, means secured to the body portion and extending between the supporting members, said means engaging the supporting members at portions thereof remote from the body portion, each of the 90 said members having a plurality of corresponding edges, the edges on each member extending at an angle with respect to each other, the said edges permitting the carton to be supported in a plurality of positions.

95 5. A dispensing carton made from a single blank, the body portion having top and back portions and side portions, supporting easel members capable of folding with respect to the side portions of the blank but 100 unsevered therefrom, a retaining member being integral with the body portion and capable of folding with respect to the blank but unsevered therefrom said retaining member being adapted to extend between the 105 said easel supporting members and being provided with extensions and said easel supporting members being provided with slots situated at portions of the easel supporting members remote from the body portion, 110 through which the said extensions extend when the blank is in folded position whereby the easel supporting members are rigidly secured with respect to the body of the 115 carton.

120 6. A dispensing carton made from a single blank having a top portion, back portion and side portions which are folded to form the body of the carton, easel supporting members which are creased with respect 125 to the side portions but are unsevered therefrom said easel supporting members having edges which extend at an angle with respect to each other, a retaining member foldable with respect to the back but unsevered there- 130

from said retaining member being adapted to extend between the said easel supporting members and being provided with projections and the said easel supporting members being provided with slots, which are situated at portions of the supporting members remote from the body portion, into which

the said projections extend when the blank is in folded position thereby forming a rigid connection between the easel supporting member and the body of the carton. 10

In testimony whereof I hereunto affix my signature.

JOHN V. HORN.
